UNITED STATES PATENT OFFICE.

CHARLES B. SHERWOOD, OF CORNWALL-ON-THE-HUDSON, NEW YORK.

SIGNAL-LAMP.

1,286,813.

Specification of Letters Patent. Patented Dec. 3, 1913.

Application filed January 26, 1917. Serial No. 146,635.

To all whom it may concern:

Be it known that I, CHARLES B. SHERWOOD, a citizen of the United States, and a resident of Cornwall-on-the-Hudson, in the county of Orange and State of New York, have invented an Improvement in Signal-Lamps, of which the following is a specification.

My invention is an improvement in signal lamps for motor vehicles, and has for its object to provide means in connection with the lamp or lamps of the vehicle, for signaling rearwardly the intention of the driver to stop or turn, wherein an auxiliary lamp is mounted at the rear of the usual lamp and adapted to be ignited at will.

In the drawings:

Figure 1 is a side view of the improved lamp with parts in section.

Fig. 2 is a rear view.

Fig. 3 is a diagrammatic view of the wiring.

The present embodiment of the invention is shown in connection with a lamp having a tapering or frusto-conical casing 1, and provided at its large end with a white lens. A reflector 3 is arranged within the casing near the large end, and an incandescent globe 4 is arranged at the center of the reflector, the reflector acting to throw the rays of light outwardly through the lens. At the small end of the casing a door 5 is arranged, the said door being hinged at 6 to the casing, and a spring latch 7 is provided for holding the door closed, the latch engaging a catch 8 on the casing.

The door is provided with a central opening, and the edge of the opening is offset inwardly to form a flange 9. A red lens 10 is seated on the flange, and a resilient split ring 11 is seated in the opening on the lens, to hold the same against the flange. An incandescent globe 12 extends inwardly from the side wall of the casing, the globe being at approximately the center of the lens 10, and a tapering reflector 13 is mounted upon

the globe and between the same and the reflector 3. The casing 1 is provided at the reflector 13 with an internal annular groove 14, for receiving the edge of the reflector 13, and the reflector is held in place by its engagement with the groove.

This globe 12 is designed to be ignited at will by means of a push button or the like, which may be arranged in any desired or convenient position. The circuit 15 for the globe 12 has interposed in the length thereof a source of supply 16, in the present instance a battery, and a push button 17, and it will be evident that by manipulating the button the circuit may be closed whenever desired to ignite the globe.

In use, when the driver intends to turn or to stop, he will press the button, thus indicating his intention to those following. As soon as the operator releases the button the circuit will be opened. The driver can always see at once whether or not his lamp is burning, because it will be in front of him.

I claim:

An automobile lamp comprising a tapering casing having at the large end thereof a lens and a reflector behind the lens, and an illuminating device carried by the reflector, a hinged door at the small end of the casing, a latch mechanism for holding the door closed, said door having a central opening, and a lens closing the opening, a reflector held within the casing in front of the lens and between the same and the first-named reflector, the casing having an annular internal groove in which the edge of the reflector seats, an electric lamp between the reflector and the lens, a circuit for the lamp, and means for closing the circuit.

CHARLES B. SHERWOOD.

Signed in the presence of—

GILBERT T. COOKS,

IRVING C. KENT.
